(57) **CLAIM**

The ornamental design for a headlamp housing for a snow thrower, as shown and described.

DESCRIPTION

FIG. 1 is a perspective view of the headlamp housing in the environment of a snow thrower.

FIG. 2 is a front view of the headlamp housing.

FIG. 3 is a left side view of the headlamp housing.

FIG. 4 is a right side view of the headlamp housing.

FIG. 5 is a top view of the headlamp housing.

FIG. 6 is a bottom front perspective view of the headlamp housing.

FIG. 7 is a bottom right perspective view of the headlamp housing; and,

FIG. 8 is a bottom left perspective view of the headlamp housing.

The broken lines in the drawings illustrate the environment and do not form a part of the claimed design. The back portion of the headlamp housing is not visible during normal use and forms no part of the claimed design.

The headlamp housing is shown with a symbolic break in its length. The appearance of any portion of the article between the break lines forms no part of the claimed design.

The labels used herein to describe orientation (e.g. front, rear, left, right) are merely for reference and are not intended to limit the interpretation of the design. Applicant reserves the right to convert a portion or portions of any of the broken lines to solid lines such that the features described by those lines then form part of the claimed design, and/or a portion or portions of any of the solid lines to broken lines such that the features described by those lines no longer form part of the claimed design.
